(57) **CLAIM**

The ornamental design for an earphone and earphone box, as shown and described.

DESCRIPTION

FIG. 1 is a front perspective view of an earphone, of the earphone and earphone box, showing my new design, shown separately for ease of illustration;

FIG. 2 is a rear perspective view of an earphone in FIG. 1. FIG. 3 is a front elevation view of an earphone in FIG. 1. FIG. 4 is a rear elevation view of an earphone in FIG. 1. FIG. 5 is a left side elevation view of an earphone in FIG. 1.

FIG. 6 is a right side elevation view of an earphone in FIG. 1.

FIG. 7 is a top plan view of an earphone in FIG. 1.

FIG. 8 is a bottom plan view of an earphone in FIG. 1. FIG. 9 is an enlarged view of a portion of the earphone labeled 9 in FIG. 2.

FIG. 10 is a front perspective view of an earphone box, of the earphone and earphone box, shown separately for ease of illustration;

FIG. 11 is a rear perspective view of an earphone box in FIG. 10.

FIG. 12 is a front elevation view of an earphone box in FIG. 10.

FIG. 13 is a rear elevation view of an earphone box in FIG. 10.

FIG. 14 is a left side elevation view of an earphone box in FIG. 10.

FIG. 15 is a right side elevation view of an earphone box in FIG. 10.

FIG. 16 is a top plan view of an earphone box in FIG. 10. FIG. 17 is a bottom plan view of an earphone box in FIG. 10; and,

FIG. 18 is a front perspective view of assembly of an earphone and an earphone box showing my design, showing the earphone box accommodating the earphone and the earphone box in an open position.

(Continued)

The broken lines depict portions of the earphone and earphone box that form no part of the claimed design.

1 Claim, 18 Drawing Sheets
